UNITED STATES PATENT OFFICE.

FREDERICK B. RYAN, OF NEW YORK, N. Y.

COMBINED DISPLAY AND ATTENTION-DIRECTING CARD.

Application filed June 26, 1925. Serial No. 39,786.

This invention relates to a combined display and attention directing card for use in connection with articles of merchandise, and has for its object to provide, in a manner as hereinafter set forth, a card of such class for quickly directing attention to a particular article of merchandise, as well as further displaying the properties of the article for the purpose of promoting the sale of the latter.

A further object of the invention is to provide, in a manner as hereinafter set forth, a combined display and attention directing card for articles of merchandise, and capable of being removably connected to the article of merchandise with which it is associated and further when connected to the article maintained by the latter in article displaying and attention directing position.

Further objects of the invention are to provide, in a manner as hereinafter set forth, a combined display and attention directing card, which is simple in its construction and arrangement, strong, durable, thoroughly efficient in its use, conveniently connected directly to the article with which it is associated for the purpose of directing attention and displaying the properties of the article, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is an elevation of a combined display and attention directing card, in accordance with this invention, showing the adaptation thereof in connection with an article of merchandise.

Figure 2 is a section on line 2—2, Figure 1.

Figure 3 is an elevation of a combined display and attention directing card, in accordance with this invention.

Figure 4 is a view similar to Figure 3, of a modified form.

Referring to the drawings, 1 indicates a container for an article of merchandise and

which is in the form of a rectangular box constructed from a foldable blank and formed with a hinged end closure 2, provided with a flap 3, which, when the closure 60 is in active position, is arranged against the inner face of the front wall 4 of the box. The hinged closure provides means whereby the contents of the container can be removed when desired. The outer face of the front 65 wall 4 is provided with suitable indicia, as at 5, to indicate the character and name of the merchandise contained by the box. A combined display and attention directing card, in accordance with this invention, is 70 adapted to be detachably connected to that end of the box 1 which is provided with the hinged closure 2, and when so connected the card is disposed in a vertical position for quickly directing attention to the article of 75 merchandise as well as further displaying and setting forth the properties of the article for the purpose of promoting the sale of the latter. The manner in which the card is held when connected to the box 1 is shown 80 in Figure 1.

A combined display and attention directing card, in accordance with this invention and as shown in Figures 1, 2 and 3 comprises a body portion of substantial height and 85 width and which is referred to generally by the reference character 6. The body portion 6 includes a semi-elliptical part 7 and a segmental part 8 of less height than the semi-elliptical part 7. The part 8, at its lower 90 end, is formed with a triangular-shaped extension 9, which at one side merges into the inner side of the part 7. The shape of the body portion 6 is such that the major part of its edge, as indicated at 10, will be upon a volute curve and the remaining part formed of angularly disposed portions 11, 12 and 13. The portion 11 terminates at its inner end in the inner end of the part 10 and projects downwardly and at an inclination 100 therefrom. The portion 12 is upon a downward inclination and extends inwardly from the outer end of the portion 11 to the outer end of the portion 13, and the latter terminates in the inner side of the semi-elliptical part 7 of the body portion 6. The edge portion 13 is disposed at right angles with respect to the part 7 of the body portion 6 and is of greater length than the angularly disposed edge portions 11 and 12. The inner 105 side of the part 7 of the body portion 6 is indicated at 14.

The outer face of the body portion 6 is provided with a direction means leading in a direction towards the box 1, and said means consists of the representation of an arrow head 15 and an elongated tail 16, and with the latter conforming in contour to the shape of the part 7 and to the shape of the major portion of the part 8. The arrow tail 16 is in the form of a volute curve, conforms in contour to the part 10 of edge of the body portion and is positioned in close proximity to said edge part 10. The direction means is of a different color from the color of the outer face of the body portion 6.

15 The outer face of the body portion 6 is provided with suitable indicia, as at 17, for displaying and setting forth the properties of the article of merchandise with which the card is associated or connected to, and said 20 indicia can consist of any suitable advertising matter.

Formed integral with the inner side of the part 7 of the body portion 6 and spaced from the edge portion 13 of the body portion 25 6, as well as tangentially disposed with respect to the lower portion of the latter, is a rectangular attaching or connecting tongue 18 of a width slightly less than the height of the wall 4 of the box 1, and said tongue 18 30 is adapted to be inserted in the box 1, between the flap 3 and the front wall 4, and when so positioned the body portion 6 will be connected to the box 1, at one end thereof, and be held in a vertical position so that 35 the indicia and directing means thereon will quickly direct attention to the article of merchandise with which the card is associated, and furthermore set forth the properties of such article and which will promote 40 the sale of the latter.

The tongue 18 is set up with respect to the body portion 6 so as to provide a substantially elongated slit or passage 19 between the tongue and the lower edge of the triangular extension 9. The inclined or bevelled edge part 12 is arranged at the open end of the slit 19 and which prevents the end of the box engaging with the body portion 6 during the positioning of the tongue 18 within 45 the box. When the card is connected with the box through the medium of the tongue 18, the triangular shaped extension 9, overlaps the top of the box, see Figure 1, so that when the card is in displayed position it not 50 only overlaps but projects from that end of the box to which it is connected. The card projects upwardly and laterally from the end of the box referred to.

55 In the form shown in Figure 4, the body portion of the card is generally indicated at 20 and is formed of a semi-elliptical part 21 and a segmental part 22 of materially less height than the part 21 whereby the lower portion of the part 21 will be positioned below the lower end of the part 22. The edge

23 of the body portion 20 is upon a volute curve and extending from that portion of the part 21, which is arranged below the lower end of the part 22 is a tangentially disposed tongue 24 of a length greater than 70 the widest portion of the part 22, whereby the tongue 24 will project beyond said part 22. The lower edge 25 of the tongue 24 forms a continuation of the arc of the edge 23 of the body portion 20.

75 The vertical edge 26, as well as the top edge 27 of the tongue 24 is squared. At the point of joinder of the tongue 24 with the part 21, it is spaced from the lower end of the part 22, as at such point the tongue 24 is 80 of less height than that portion of the part 21, which is arranged below the lower end of the part 22.

The outer face of the body portion 20 is provided with suitable indicia, as at 28, for 85 the purpose of setting forth the properties of the article of merchandise with which the card is associated, as well as any other suitable advertising indicia. The outer face of the body portion 20 is provided with direction means extending towards the article of merchandise to which the card is attached, and said direction means is the representation of an arrow having the head thereof indicated at 29 and the tail at 30. The tail of 90 the arrow is upon a volute curve and the major portion thereof is positioned in proximity to the edge 23 of the body portion 20.

95 When the form of card as shown in Figure 4 is employed, the tongue 24 is inserted 100 between the flap 3 and front wall 4 of the container or box and when so positioned the segmental part 22 of the body portion 20 overlaps the top of the box or container. When the tongue 24 is inserted in the box or 105 container, the card is maintained in vertical position with respect thereto and not only overlaps that end of the box to which it is attached, but extends upwardly and laterally therefrom.

110 It is thought that the many advantages of a combined display and attention directing card, in accordance with this invention can be readily understood, and although the preferred embodiment of the invention is as 115 illustrated and described, yet it is to be understood that changes in the details of construction can be had which will fall within the scope of the invention as claimed.

115 What I claim is:—

120 1. A combined article of merchandise display and attention directing device for detachable connection to the end of a carton containing such merchandise comprising a vertically disposed body portion of an area 125 to contain means for displaying the properties of and for directing attention to the article with which the device is employed, and an attaching tongue projecting laterally from the inner side of the lower part of 130

10 said body portion for insertion into one end of the carton with which the device is used to maintain said body portion extending upwardly at right angles with respect to said end, the lower end of said tongue forming a continuation of the edge of the body portion to space the latter from the support for the carton, said body portion of materially greater height than that end of the carton 10 with which the body portion is detachably connected.

2. A combined article of merchandise display and attention directing device for detachable connection to an end of a carton 15 containing the article comprising a vertically disposed body portion having a reduced lower part, said body portion of an area to contain means throughout for displaying the properties of and for directing attention to 20 the article of merchandise with which the device is employed, and an attaching tongue projecting laterally from the inner side of the reduced lower part of said body portion for insertion into one end of the carton containing the article with which the device is 25 used for maintaining said body portion in vertical position to extend upwardly at right angles with respect to such end of the carton, the lower edge of said tongue forming 30 a continuation of the edge of the body portion to maintain the body portion when attached to the carton in spaced relation with respect to the support for the carton, and the wider part of said body portion overlapping 35 the top of the carton at that end into which the tongue is inserted.

3. A combined article of merchandise display and attention directing device for detachable connection to an end of a carton

containing the article comprising a vertically disposed body portion of an area to contain throughout means for displaying the properties of and for directing attention to the article with which the device is employed, said body portion having a reduced lower part, an attaching tongue projecting laterally from the inner side of and of less height than said lower part of said body portion for insertion into one end of the carton with which the device is used for 40 maintaining said body portion in vertical position with respect to said end, said body portion of materially greater height than the carton to which it is attached and having the major part of its edge of convolute curvature, and said tongue being rectangular in contour and having its lower edge forming a tangentially disposed continuation of the convolute edge of the body portion to maintain the latter spaced above the support on 45 which the carton is mounted when the tongue is inserted into the latter, said tongue having its upper edge disposed at right angles with respect to a part of the non-convolute portion of the edge of the body portion, the 50 said upper edge of said tongue spaced from and in close proximity to the remaining part of the non-convolute portion of the edge of the body portion to provide in connection with the latter a slit to form a clearance 55 for the reception of the top of the carton whereby the wider part of the body portion will overhang the carton when the tongue is inserted into one end of the latter.

In testimony whereof, I affix my signature 60 hereto.

FREDERICK B. RYAN.
